DESIGN FOR A COMBINATION BOTTLE CAP REMOVER AND CORK SCREW

Myron A. C. Johnson, Coral Gables, Fla.

Application November 17, 1944, Serial No. 116,393

Term of patent 7 years

(Cl. D44—29)

To all whom it may concern:

Be it known that I, Myron A. C. Johnson, a citizen of the United States, residing at Coral Gables, in the county of Dade and State of Florida, have invented a new, original, and ornamental Design for a Combination Bottle Cap Remover and Cork Screw, of which the following is a specification, reference being had to the accompanying drawing, forming part thereof.

Figure 1 is a side elevational view of a combination bottle cap remover and cork screw showing my new design.

Figure 2 is a bottom plan view thereof.

Figure 3 is an end elevation.

I claim:

The ornamental design for a combination bottle cap remover and cork screw, as shown.

MYRON A. C. JOHNSON.
